EGG CANDLING BOOTH

Preston J. Blackwell, Emerson, N. J., assignor, by
mesne assignments, to Robert Gair Company,
Inc., New York, N. Y., a corporation of New
York

Application May 15, 1946, Serial No. 669,748

4 Claims. (Cl. 88—14.5)

1

This invention relates generally to the candling of eggs—an art which is practiced today in a way which differs very little from that which has continued through many, many years. In large establishments where candling operations proceed on a big scale, it is customary to provide a relatively dark room for a number of operators, usually women, who must stand continuously while performing their work. The cases of eggs to be candled are moved about exteriorly of the room by handlers who place the cases within reach of the operators who then remove the eggs, for grading, one at a time, with the aid of the usual candling light. As each case becomes empty, it should be moved or shifted to an out of the way position. The eggs, as candled, are deposited in open cartons (if good), in fillers (if spoiled), or in other cases (if classified as "under-grade" or as "crax"). As each carton or case is filled, it is moved by pushing on to a conveyor to be removed from the room. The facilities provided for each of the operators are much the same; each is required to take certain steps to move into convenient position for different phases of the work; each operator must reach over from time to time in order to move or grasp the articles or objects with which she is working; and each is obliged to remain standing during this entire operation. Because of the tiring and generally unsatisfactory conditions attending the operation of candling as now performed, considerable fatigue is experienced during the course of the day. Although rest periods may be provided, the quality of the work inevitably suffers as weariness increases. This is particularly noticeable toward the close of the day. Because of these various reasons, this type of work is not attractive, and even those who have undertaken to do it readily accept other work, so that the labor turnover is large and costly.

Realizing all these present-day shortcomings which attend the art of candling as now practiced in large institutions, I have sought by my invention to simplify, facilitate, and economize on the movements and operations necessary in the candling of eggs. As a primary consideration, I provide a comfortable seat in which the operator may remain continuously while performing the necessary duties. Every facility required in the performance of the work is maintained conveniently at hand, and when replacements, shifting of materials, cases or further supplies are needed, these may be brought to hand or removed with but very little effort, and without any extended reaching or movement on the part

of the operator. This desirable objective is attained because of a special and unique arrangement of cases, cartons, etc., as well as the supports and the delivery and conveying means which I have provided. Each operator may work alone in a booth with all needed facilities conveniently at hand. As a result of the means thus provided, an operator who remains continuously seated during her work will undergo little or no fatigue, and experience has shown that the quality of her work will be satisfactory and uniform over an extended work day period.

As indicative of a means whereby the art of candling may be practiced according to my invention, I have illustrated in the accompanying drawings an exemplification thereof wherein;

Fig. 1 is an elevational view of the exterior of two in-line booths, one of which has its walls partly broken away to exhibit the interior thereof;

Fig. 2 is an enlarged fragmentary section transversely of the booth, looking from a point rearwardly of the seat therein;

Fig. 3 is a longitudinal section, taken on line 3—3 of Fig. 2;

Fig. 4 is a detail in section, taken on line 4—4 of Fig. 1;

Fig. 5 is a detail in section through the rear end wall of the multiple booths, showing the conveyor chain at its point of reversal exteriorly of and beyond the end booth;

Fig. 6 is a detail in vertical section of the carton conveyor at one of the junction points where a branch chute leads to the adjacent booth;

Fig. 7 is an enlarged fragmentary detail, in section, of the delivery end of the carton chute; and

Fig. 8 is a detail, more or less diagrammatic, of the signal system by which notice is automatically given of an approaching deficiency in the supply of cartons available for an operator within one of the candling booths.

In the preferred arrangement, multiple booths are provided; that is, two or more booths are arranged in line so as to be served by a common conveyor system. Most, if not all, of the mechanism herein to be described is duplicated for each booth, so that a description of but one will suffice. The booths are sufficiently closed to exclude much of the light from the surrounding room, appropriate walls 10 being provided for this purpose. A door 11 communicates with each booth to permit access thereto.

At a point which is more or less central of each booth, I provide a swivel chair or seat A which may be mounted on swivel casters 15 to facilitate

movement of the chair out from one booth into another, in case the operator is to be transferred to another location. It is important that the chair be comfortable, and for this purpose a so-called "posture" chair is suggested. Such a chair may be adjusted to meet the requirements of the operator who may then sit and work in a straight, upright position over a considerable time with a minimum of fatigue.

The operator, when seated, will occupy a position directly in front of a candling light B of any approved construction. This includes a casing with a peep opening 16 facing the operator and before which each egg is successively held to determine its quality and grade. The uncandled eggs may be contained in the usual case C, centrally divided by a partition 17 which provides two compartments in each of which the eggs are packed within fillers with intervening flats, arranged in tiers from bottom to top. This case, as well as a second case in reserve and in end to end relation therewith, may be moved endwise into the booth through an opening 18 of only slightly larger size. Each case is supported in an inclined position upon rollers 20 so as to maintain its open upper side tilted toward the operator. So that these cases may move freely in an endwise direction while remaining on the roller support, I provide along their forward sides a second set of rollers 21. In this way an angled roller support is provided for the cases whereby each may be successively shifted, endwise of itself, with a minimum of effort from a point exteriorly of the booth into a position directly before the operator, with its two compartments disposed below and on opposite sides of the candling light. The case remains tilted always toward the operator whereby to minimize the distance of reach for removal of eggs therefrom. When each case is empty, it is then ready for use elsewhere or to be lifted on to a conveyor (later to be described) at the operator's side which is opposite that from which the case entered the booth. The second case of uncandled eggs still held in reserve is then pulled by the operator to an operative position directly before her, and this is followed later by the handler, who is in attendance exteriorly of the booths, placing another reserve case on the roller support 20-21 within reach of the operator within the booth. The presence of one or more cases on the roller support 20-21 acts to exclude much of the light which otherwise might enter through the opening 18 into the booth.

To the same side of the operator is another roller support 23 which exteriorly of the booth is horizontal, and therewithin is slanted downwardly with a stop 24 at its lower end (see Fig. 4). This support is to receive a case D having opposite sides cut-away to provide, in effect, a rack wherein may be stacked collapsed fillers. When full, this rack is pushed out through a booth opening 25 which it substantially occupies to exclude light from passing into the booth. In this position of the rack exteriorly of the booth the handler will tie into a bundle the collapsed fillers which are then removed. The empty rack is then pushed in again to a position beside the operator within the booth wherein it remains tilted toward her to facilitate placing of empty collapsed fillers therewithin.

At the opposite side of the operator is another roller support 26 for cases E, in end to end relation, one to receive crax and the other eggs which are undergrade. It will be understood that the term "crax," as commonly employed in the trade,

is used herein to define an egg with a broken shell. This support which is elongated to extend forwardly and rearwardly is also inclined to tilt each case toward the operator. At the far side of this support, about in line with the top surface of its rollers, are swivel casters 27 arranged in one or more rows. These casters lie about opposite the lower run of a chain conveyor 28 which moves in channels 29 supported upon a framework 30. By sliding a case E sidewise of itself and endwise of its supporting rollers 26, and then over the swivel casters 27, the case is brought to position upon the chain conveyor which takes it away to a distant station. This is the procedure when one of the cases E is filled. An empty case E to receive further crax or undergrades may be brought by the conveyor to a position opposite its roller support at which point the operator may draw the empty case toward her with little or no effort, so as to bring it to an inclined position of rest upon the roller support and against a stop 31 which may be formed conveniently from an angle iron, as best shown in Fig. 2. It is contemplated also that empty cases C from which eggs have been removed for candling may be available for transfer to the roller support 26 whenever needed.

In practice two cases, arranged end to end, will normally be positioned on the inclined roller support adjacent the operator. One of these cases will receive undergrade eggs and the other eggs which are cracked. Both of these grades of eggs are commercially in demand, consequently I have provided in the present equipment a suitable means for supporting and conveying cases intended for their reception. When full and removed by the conveyor, an empty case in replacement will usually be available from the roller support 20-21 in front of the operator, since the rate of emptying the cases C containing eggs to be candled usually exceeds substantially the rate at which the cases E are filled with eggs which are undergrade or cracked. The excess of the empty cases C may be placed on the top run of the conveyor for removal to the front end of the booth line.

As the operation of candling proceeds, the good eggs, i. e. the first and second grade eggs, are deposited in separate cellular cartons F. For this purpose I provide, just forwardly of the case C, a way or trough w forming a support which extends transversely across the booth. This carton support which is inclined toward the operator may comprise a bottom 33 from which rises a slanting front wall 34 whose top edge at spaced points is about flush with the corresponding adjacent edge of the case C. This way which is of a length something greater than that of two cartons may be closed at one end by a wall 35, but at its other end which is open is formed into a downwardly slanted runway 36 which terminates adjacent and slightly above one edge of the lower run of a conveyor belt 38 whereon the filled cartons may be slid from time to time.

The operative positions of two cartons, end to end, are immediately behind the rear wall of the case C, below the candling light, and spaced slightly apart to lie on opposite sides thereof (see Fig. 2). Each carton F will then stand substantially opposite one of the two compartments of the egg case C from which the eggs are successively removed for candling. Each egg which tests up to grade may then be placed in one of the two cartons until all the cells thereof are filled. When this stage is reached, the two car-

tons may be slid endwise through the way (to the right as viewed in Fig. 2) to ride down the inclined runway 36 onto the conveyor belt 38 for removal to a take-off station exteriorly of the booth.

To the left of the case C containing uncandled eggs (as viewed in Fig. 2), I provide a shelf 40 which extends alongside the operator. This shelf has two levels, the upper being to the front just over the opening 18, and the lower to the rear just over the opening 25. The upper tier of this shelf is provided for the reception of flats c as taken from the case C, and the lower tier for the reception of erected fillers d (and flats) into which spoils (leakers, rots, jumbos, etc.) may be placed from time to time. The accumulated fillers and spoils may be removed periodically by one of the handlers—preferably when the operator is absent from her booth.

The apparatus herein disclosed is especially advantageous when employing cellular egg cartons F which, when erected but before closing, have diverging sides x and y extended a considerable distance above, and outwardly from, the top of the carton cells. As shown in Fig. 3, the near one of these diverging walls (which in a later operation is folded inwardly to provide a closure, partial or complete, for the carton), extends upwardly to terminate about flush with the top edge of the case C so as to minimize the operator's reach necessary for placing candled eggs in the carton. When filled and pushed off the way on to the conveyor, empty cartons stand conveniently at hand ready for placement in the way so that the candling operations may proceed without interruption. This supply of waiting cartons is contained in an overhead feeding chute in conjunction with a conveyor system, as will now be explained in detail.

Over each carton as it stands in operative position within the way w is the delivery end 42 of a chute G which proceeds upwardly through a curve and then through an inclined portion 43 to join at its top with a feeding mechanism which includes a slider board 44 with opposite side walls 45 extending lengthwise of the in-line booths. Two of the delivery chutes G in parallel, slightly spaced, relation are provided so that cartons emerging from the lower ends thereof will automatically drop into positions, on opposite sides of the candling light, within the way. Since the two chutes and the feeding mechanisms with which they are connected are identical, a description of but one will suffice.

At the point where each chute joins with the slider board, I provide a trap door 46 which is hinged at 47 to swing from a horizontal position flush with the slider board to one which aligns with the inclined under wall of the chute G. This door may be operated mechanically to move from its closed position shown in full lines in Fig. 6, where it preserves continuity with the slider board, to an open position which is indicated by broken lines. For this purpose I may employ a bracket 48 depending from the trap door, and in pivotal connection therewith a pair of hinged links 49 and 50, the latter being pivotally joined to a fixed bracket 51. A link 52 which is pivotally joined at one end to the link 50 is also connected to the plunger 53 of a solenoid 54 which, when electrically energized through a circuit which includes the wires m and n, will exert a pulling force on the link 50 sufficient to break the two links 49 and 50 at their point of interconnection. The trap door 46 will thereupon be

drawn down to open position against the tension of a spring 55. When the solenoid is de-energized, the spring 55, exerting its force against the link 49, will return the trap door to its closed position where it is held by the links 49 and 50 in their straight line position. This is a simple, yet effective, form of mechanism for permitting cartons advancing along the slider board 44 to continue on past the trap door when the latter is horizontally sustained, or to drop through the opening vacated by the door to enter into the chute G and descend by gravity toward the delivery end thereof.

At a point adjacent its delivery end, there is affixed across the rear wall of the chute a wedge block 56 having its maximum width toward the bottom. On the opposite chute wall is a friction stop 57, of rubber or the like, projecting into the chute for varying distances in accordance with adjustments of a screw 58. The friction stop exerts its pressure at a point above the wedge block so that the carton therebetween will be engaged at offset places, one being opposite the cellular body and the other opposite the free end portion of a diverging side wall of the carton. Crushing or damage to the carton is thereby avoided. When the lowermost carton is in process of being withdrawn, the friction stop will engage the next succeeding carton to arrest its descent prior to complete freeing of the bottom-most carton, thereby preventing any accelerated movement of the carton stack which otherwise might become uncontrollable.

The erected cartons descending through the chute are in semi-nested relation, i. e. the diverging and upwardly extending side walls of one carton receive between them the cellular body structure of the next adjacent carton; the front and rear walls of the chute press inwardly against the side walls of each carton to deflect the same inwardly toward the next adjacent carton. So long as the lowermost carton remains supported at the bottom end of the chute, those above will be sustained in stacked relation therewith. The constriction provided by the block 56 and the friction stop 57 is sufficient to support the bottommost carton with its body structure depending below the bottom end of the chute. Because of this exposure the operator may conveniently seize hold of the lowermost carton to withdraw it from the chute, and when so doing the cartons thereabove will descend a distance substantially equal to the body height of the carton so removed. The obstructions placed at the bottom of the chute act to support successively each lowermost carton, thereby sustaining the entire stack within the chute.

As each carton is filled with candled eggs, it is pushed endwise through the way w down its runway 36 and onto the conveyor belt 38. At about the same time the operator will reach out to seize another lowermost carton in one of the overhead chutes G, which, when removed therefrom, will drop into the way w where it may be placed in the position of maximum convenience for receiving graded or candled eggs. This procedure is followed during the entire candling period so that the operator need give no concern to the supply or disposal of cartons with which she is working.

Each operator will be free within considerable limits to employ the apparatus herein disclosed in the way that best meets existing conditions or her preference as to procedure. For example, the testing of eggs may call for separation into

three grades, so that the way should desirably accommodate a third carton F in addition to the two already noted. In such a case, the extra carton to be filled might be placed at the left end. The standard or average run of acceptable eggs will test out perhaps eight or nine times as many first grade eggs as those of the second grade, and an even greater ratio in relation to eggs of the third grade. In such circumstances the carton to the right would probably be used for receiving the top grade eggs since in that position, from which filled cartons are to be moved most often, the distance to the conveyor is least and there is no interference to movement of that carton on to the conveyor at any time. For the same reason, the chute G standing to the right will be called upon to deliver many times as many empty cartons as the companion chute to the left.

The slider board 44 underlies a belt 60 whose spacing above the board is slightly less than the normal full width of the empty cartons to be advanced. As shown in Fig. 6, the belt engages the nested cartons, thereby inwardly deflecting their diverging sides, and frictionally advancing the cartons along the slider board to their several destinations. This belt is mounted to travel overhead with respect to the in-line booths, being trained over a pulley 61 at the rear end, and at the forward end making an angular downturn over a pulley 62 to execute a return bend around a pulley 63 which is mounted on a suitable framework at the front end of the aligned booths. The slider board 44 also executes a bend at 64 to proceed downwardly, its lower end 65 terminating close to a platform 66 which is at the delivery end of an automatic carton setting-up machine (not shown).

The lower and inside run of the belt 60 is trained around a pair of closely spaced idler rolls 68 and over a third idler roll 69 which is disposed above and between the others. By following this tortuous path, the inside run of the belt is maintained away from the slider board a sufficient distance for movement of cartons along the slider board while executing a change in its direction of travel corresponding in general to that of the downwardly curving slider board. The belt is sufficiently relaxed to follow a curved path, as required, while the cartons are proceeding upwardly over the curved portion of the slider board. A lower belt 70 is mounted to train over a pulley 71 coaxial with the pulley 63, and also over a lower pulley 72 which is located close to the end of the slider board adjacent the setting-up machine platform 66. Feeding of the cartons is initiated by the lower belt from which the cartons are transferred to receive feeding engagement from the main belt 60.

Each case E containing crax or undergrades, after being pushed onto the conveyor chain 28, is advanced lengthwise of the booths and outwardly therebeyond (see Fig. 5). Here it may be deflected laterally onto a table to await removal by one of the handlers in attendance. This chain is trained at one end over upper and lower sprocket wheels 75 and 76, mounted on a suitable framework exteriorly of the rear end of the booths, so that the upper and lower runs of the chain will be properly spaced. At its opposite or forward end, the chain is trained over upper and lower sprocket wheels 77 and 78, respectively (see Fig. 1). The carton conveyor belt 38 is mounted to travel over pulleys 79 and 80 at opposite ends of the booth system.

For efficient operation of the apparatus herein

disclosed, I contemplate the provision of suitable controls exteriorly of the booths at a point relatively close to the platform 66 where an attendant will regularly be stationed so as to be available to manipulate these controls, as necessary. The setting-up machine will be timed to deliver cartons in clusters of perhaps twenty, with a spacing of a foot or so therebetween. In case the output of the setting-up machine is too fast, its operation may be slowed down or temporarily stopped.

At a point in each chute G remote from its delivery end a distance of about ten stacked cartons, I may provide a movable finger 82 here shown as pivoted (see Fig. 8) which may be so weighted as to normally project inwardly of the chute for successive engagement with the proximate sides of each carton descending therethrough. As long as the carton stack is made up of ten or more cartons, this finger will be held in a retracted position. When the number of such cartons drops below ten, then the finger is free to swing inwardly, and when in this position closes a gap in an electrical circuit through the wires s and t whereby to energize a warning signal 83 that is located in proximity to the delivery table 66. This signal will apprise the attendant at that point that an identified booth is running short of cartons. By operating a suitable control 84 to close an electrical circuit through the wires m and n which energizes the solenoid for operating a trap door, the next advancing cluster of cartons advancing along the slider board will be switched by gravity into the open chute G to replenish the low stack at that point. In this way the signal automatically given to the machine attendant will call for action whereby a predetermined quantity of empty cartons will be fed into the low-supply chute. During this operation, the candling operator may continue uninterruptedly with her duties without any thought or attention to the problem of supply.

In practicing the art of candling according to my invention, it is possible for each candler to remain seated during all of the movements which are required. No lifting of any case is required, except by handlers who are stationed exteriorly of the booths. The feed of empty cartons proceeds automatically from the machine which sets them up, desirably in clusters to facilitate their movement to the supply chutes where they are stored convenient to the several candling operators. The work which is performed according to this method and apparatus is both expeditious and non-fatiguing since all manual operations are minimized, and this is reflected in a noticeable improvement in the results obtained.

I claim:

1. In a candling apparatus, the combination with a substantially darkened booth wherein is an operator's seat, of a tilted support, extending from a point before the operator within the booth to a point exteriorly thereof, for receiving egg cases adapted to be slid endwise thereon successively to a position before and tilted toward the operator, a candling light over said support forwardly of the operator's seat, and a second support within the booth alongside said first mentioned support inclined toward the operator adapted to sustain a filler rack in a position tilted toward the operator, there being adjacent openings through one booth wall opposite the two supports, one of said openings conforming to an egg case and the other to a filler rack to be substantially closed by a case and a rack when

mounted on said supports thus maintaining the darkened condition within the booth.

2. In a candling apparatus, the combination with a substantially darkened booth wherein is an operator's seat, of means providing an anti-friction support for an egg case in front of the operator's seat, a candling light over said means forwardly of the operator's seat, a slideway for supporting an egg carton below the light and rearwardly of said case supporting means, an anti-friction support for a filler rack alongside said case supporting means to one side of the operator, there being formed in an adjacent wall of the booth openings through which the egg case and filler rack may be slid on their respective supports, one of said openings conforming to an egg case and the other to a filler rack to be substantially closed respectively by an egg case and filler rack when stopped therein thus maintaining the darkened condition within the booth, an anti-friction support to the opposite side of the operator for a second case, and dual conveyor means one at one end of the carton slideway for moving filled cartons to a distant point and the other at one end of the second case supporting means for removal of cases to a distant point.

3. Egg candling apparatus consisting of a substantially closed darkened booth provided with an inlet opening in a wall thereof for the reception of successively fed filled cases of eggs, said opening being substantially closed by an egg case when positioned therein thereby maintaining the darkened condition within the booth, means ex-

tending from a point exteriorly of the booth through the inlet opening and into the booth forming a support along which a plurality of egg cases may be successively advanced into the booth and supported in operative position therein, a candler's seat in the booth, and a candling light positioned adjacent the candler's seat and proximate egg case, whereby the candler, in a sitting position, may candle the eggs from the case.

5 4. In egg candling apparatus, the combination of a substantially darkened booth having a filled egg case inlet opening conforming to an egg case, means for supporting a succession of egg cases at and within said opening to substantially exclude outside light from the interior of the booth, means for supporting an egg case within the booth in line with the inlet opening, a candler's seat in the booth in front of the last mentioned case supporting means, and a candling light positioned in the booth over the last mentioned case supporting means and forwardly of the candler's seat whereby the candler, in seated position in the booth, has ready access to eggs in said supported egg case.
